UNITED STATES PATENT OFFICE.

THOMAS L. OLIVER, OF CEDAR GROVE, NORTH CAROLINA.

SOFT-DRINK-VENDING MACHINE.

1,210,520.

Specification of Letters Patent.

Patented Jan. 2, 1917.

Application filed July 7, 1916. Serial No. 108,001.

To all whom it may concern:

Be it known that I, THOMAS L. OLIVER, a citizen of the United States, residing at Cedar Grove, in the county of Orange and State of North Carolina, have invented a new and useful Soft-Drink-Vending Machine, of which the following is a specification.

The object of the invention is to provide a simple and inexpensive apparatus by means of which bottled goods, particularly soft drinks of one or different varieties, may be vended under coin actuated conditions, and wherein the liability of breakage may be minimized.

Further objects of the invention will appear as the description proceeds, it being understood that changes in the precise embodiment of the invention herein disclosed, can be made within the scope of what is claimed, without departing from the spirit of the invention.

In the drawings:—Figure 1 is a vertical sectional view taken in a plane parallel with the front of the vending machine to show the interior construction and mechanism. Fig. 2 is a vertical sectional view taken on the plane indicated by line 2—2 of Fig. 1. Fig. 3 shows the coin controlled mechanism with the parts arranged in the positions which they will assume when a coin is deposited. Fig. 4 is a view similar to Fig. 3 showing the movement of the parts as the bottle holding mechanism is moved to release a package. Fig. 5 is a detail vertical sectional view on the plane indicated by the line 5—5 of Fig. 3.

The casing 10 of the apparatus may be arranged to vend one or more kinds of goods as for example, Coca-Cola, Pepsi-Cola, gingerale, etc., and in the construction shown two compartments are illustrated with storage compartments 11 and 12 arranged at their upper ends on either side of an ice compartment 13 which together with the storage compartments for the goods may be reached by opening a rear door 14 in the casing. Also for convenience, a spigot 15 may be arranged in communication with the ice compartment at the front of the casing and glass panels may be arranged in the upper vertical portions of the storage compartments or runways so that the goods may be seen therethrough. The storage compartments or runways 11 and 12 are preferably converged toward

their lower ends as shown at 16 and 17 and terminate in the vertical legs 18 and 19 where at the lower end each is controlled, for the purpose of delivering a single bottle 60 or package at a time, by holding mechanism, only one of which however is illustrated in the drawings, as said devices will be duplicates. The holding mechanism consists of upper and lower blades 20 and 21 adapted 65 to be alternately advanced and retracted in a direction across the runway or storage compartment, the column of bottles or packages being normally supported by the blade 21 and, when the latter is withdrawn to 70 liberate a package, the other blade 20 is advanced to separate the package to be delivered from those of the column above it so as to restrain the latter until the blades are again reversed in position (after the delivery of the lowermost package), whereupon the packages again are supported by the lower blade. In order to break the jar due to the advance of the packages in the column after the lowermost package has been 80 discharged, the blades are provided with cushioning plates 22 of resilient material, sufficient in strength to support the column of articles and yet permit it to yield sufficiently to avoid breakage. It will be noted 85 that these cushioning plates do not extend entirely across the storage compartment or runway but terminate preferably at an intermediate point, so that the full benefit of 90 the resilience thereof may be secured.

In the construction illustrated the supporting blades are connected with an operating handle 23 which extends to the outside of the casing, being normally held in a repressed position by a spring 24 and having 95 a cross head 25 to which said blades are pivotally attached. The operating handle is normally in a depressed position and when raised after a suitable manipulation of the coin controlled mechanism the upper blade 100 20 is advanced as above noted and the lower blade is withdrawn to release the lowermost package.

Communicating with a slot 26 preferably in the front of the casing is a coin chute 27 105 arranged to deposit a coin of the proper denomination in the pocket 28 of a latch 29 which is pivoted as at 30, a stop pin 31 preferably being located to prevent the premature release of the coin. The parts are so 110 proportioned that with a coin of the proper denomination in the pocket of the latch, the

2
latter will be depressed at the pocket end to bring its other end in contact with a check member 32 pivoted as at 33, and held from dropping below its normal position by a stop pin 34. The free end of the check member is arranged in the path of the rear end of the latch and offers sufficient resistance to prevent the depression of the pocket end of the latch to an extent sufficient to 10 release the coin.

One of the holding or supporting blades (preferably the upper member thereof) is provided with a cam or wedge 35, terminating at its forward end in a shoulder 36 which is normally in engagement with the latch and is thereby locked to prevent the movement of the holding mechanism. When, however, a coin has been deposited as illustrated in Fig. 3 and the latch has 15 been depressed slightly at its pocket end to the position in which it is limited by the check member, the wedge is free to pass under the lower end of the latch, and therefore the supporting mechanism is released. 20 25 The movement of the lever 23 to discharge a package, thus withdrawing the lower blade 21 and advancing the upper blade 20, causes the wedge 35 to raise the latch at its rear or weighted end as shown in Fig. 4 and thus discharge the coin into a suitable 30 receptacle 37 provided for that purpose.

In the side of the coin chute there may be arranged a detector or release slot 38 of such a size as to permit the escape of a coin 35 smaller than that of the denomination required as the purchase price of an article to be vended by the machine,—as for example if a nickel is the standard coin for the purchase of a package the detector slot 40 will be of such dimensions as to release a penny and permit it to drop free from the mechanism without the actuation thereof as hereinabove described.

What is claimed is:—

45 1. A vending machine having a storage

compartment and supporting blades for alternate projection thereinto to intercept the objects in said compartment and connected for simultaneous movement in opposite directions, a locking latch normally engaged with one of said supporting blades and having a coin pocket, means for delivering a coin to said pocket, checking means for yieldingly limiting the movement of said locking latch, and means movable 50 simultaneously with the supporting blades for displacing the locking latch to release the coin.

2. A vending machine having a runway, 60 operatively connected supporting blades for alternately intersecting said runway, a locking latch normally in engagement with one of said supporting blades and provided with a coin pocket, a checking means for yieldingly limiting the movement of the locking 65 latch when disengaged from said supporting blade, and a cam actuated by one of said supporting blades for further moving the locking latch to release the coin.

3. A vending machine having a runway, 70 simultaneously movable supporting blades for alternate intersection of said runway, an intermediately pivoted locking latch having on one arm a coin pocket and having the other arm in engagement with a shoulder of one of said supporting blades, a pivotal checking member arranged in the path of the blade engaging arm of said locking latch for yieldingly limiting the movement of said latch, and a cam actuated by said 75 supporting blade for further moving the latch to release the coin.

In testimony that I claim the foregoing as my own, I have hereto affixed my signature in the presence of two witnesses.

THOMAS L. OLIVER.
